Primary Examiner — Barbara Fox*Assistant Examiner* — Mehri F Bajoul(74) *Attorney, Agent, or Firm* — The Myers Law Group(57) **CLAIM**

The ornament design for a “cat toy,” as shown and described.

DESCRIPTION

FIG. 1 is a perspective view of a cat toy showing my new design;

FIG. 2 is a top plan view thereof with the string truncated to show the relationship between several parts thereof;

FIG. 3 is a cross sectional view taken along the line 3-3 of FIG. 2;

FIG. 4 is a bottom plan view of the play end of the cat toy taken in the direction of line 4-4 in FIG. 2

FIG. 5 is a front perspective view of the connector element of the cat toy in a closed position;

FIG. 6 is a top plan view of the connector element of the cat toy; and,

FIG. 7 is a front perspective view of the connector element of the cat toy in an open position.

The broken lines in FIGS. 1, 2, 4, and 7 depict portions of the cat toy that form no part of the claimed design.

The drawings are shown with a symbolic break in its length and width. The appearance of any portion of the article between the break lines forms no part of the claimed design.
